CIGAR WRAPPING MECHANISM

Karl Erik Granstedt, Stockholm, Sweden, assignor to Aktiebolaget Formator, Stockholm, Sweden, a joint-stock company of Sweden

Application May 11, 1933, Serial No. 670,583
In Sweden June 3, 1932

15 Claims. (Cl. 131—45)

This invention relates to improvements in cigar-wrapping mechanisms.

In cigar wrapping mechanisms considerable difficulty has been experienced in controlling the flag of the wrapper after it has been released from the wrapper support and before it is completely wound about a cigar bunch and on providing guides such as extensions of the tension plate for such purpose the wrapper flag will be subjected to an injurious dragging action by engagement with underlying surfaces and a sufficient control will not be obtained.

The main object of the present invention is to provide a simple device for correctly controlling the movement of the flag of the wrapper until it is completely wound about the head of the cigar bunch. Another object of the invention is to provide a wrapping mechanism of the general character indicated above with an anti-friction carrier for conveying the rear- or flag-end of the wrapper from its support to the head of a bunch. Still another object of the invention is to provide a wrapper tension plate, forming part of said wrapping mechanism, with a movable carrier for conveying the wrapper flag in the manner mentioned above. With these and other objects not specifically mentioned in view, the invention consists in certain constructions, combinations and parts which will be hereinafter fully described and then specifically set forth in the claims hereunto appended.

In the drawings, Fig. 1 is a perspective view of a device constructed in accordance with the invention; Fig. 2 is a perspective view of another embodiment of the invention; Fig. 3 is a perspective view of the embodiment shown in Fig. 1, showing a nicked wrapper flag just before being wound about the bunch head; Fig. 4 is an end view of the embodiment shown in Fig. 1, showing the flag of the wrapper just being released from the wrapper support; Fig. 5 is an end view of a modified form of the wrapper tension plate; and Fig. 6 is an end view of another modified form of the invention.

Referring to the drawings, 1 indicates an almost completely wrapped bunch in a rolling mechanism forming part of a wrapping mechanism. The rolling mechanism comprises bunch rollers 7 mounted in a frame 11 in a manner well known in the art and therefore needing no further description herein. There is also provided a wrapper support 8, provided with means as for instance a suction surface for holding a wrapper in outstretched condition thereon. The suction pipe is indicated 35. The wrapper support and the mechanism for establishing suction therein

are well known in the art, and further description thereof is not needed herein.

There is further provided a tension plate 3. This plate runs in a guide 33 and has a movement by which it is periodically brought into a position adjacent the rollers 7. To this end a cam disc 25 is secured by means of a screw 24 to a shaft 12 rotatably journaled in the frame 11 and driven in any well known manner. A lever 27, 29 is pivoted to a shaft 15, its arm 27 having a roller 28 and its other arm 29 conveying the wrapper tension plate 3. The roller 28 is forced against the circumference of the disc 25 by a tension spring 30, one end of which is connected at 31 to the arm 27 and its other arm at 32 to the frame 11. The disc 25 is provided with an extension 26. The end of the wrapper tension plate 3 adjacent the head of the cigar bunch 1 is somewhat curved downwardly and provided with a roller 10 having pins 9 rotatably journaled in the tension plate 3. The cylindrical surface of the roller projects slightly above the surface of the wrapper tension plate.

It will be understood that the wrapper is held by suction in outspread condition upon the operating surface of the wrapper support 8 throughout the greater part of the relative crossing movement of said support and the bunch rolling mechanism whereby the wrapper is delivered from the support to a bunch in the rolling mechanism. It may here be remarked that the mechanism by which this relative crossing movement is produced is well known in the art, and therefore description and illustration thereof is omitted from this specification.

A lever 16, 21 is pivoted to the shaft 15. The free end of the lever arm 16 has a roller 17 and the free end of the lever arm 21 has a friction surface 22 adapted to be periodically brought into engagement with the roller 10. To this end a cam disc 13 is secured by means of a screw 23 to the shaft 12 and the roller 17 is forced against the peripheral portion of the disc 13 by a tension spring 18 connected to the arm 16 at 20 and to the frame 11 at 19. The cam disc has a curvature 14. The lever 16, 21 and cam disc 13 may, under certain circumstances, be omitted if according to Fig. 5 one end of a spring 34 is secured to one of the pins 9, its other end being connected to the tension plate 3.

In operating the mechanism illustrated in Figs. 1, 3 and 4, the wrapper held outspread upon the operating surface of the support 8 is moved in the direction of the arrow to about the position illustrated in Fig. 4. Then the wrapper

tension plate has been moved by arm 29 into a position adjacent the rolling mechanism, and is resting in such position. Thereby the operating surface of the support 8 is forcing the rear 5 wrapper end 6 and the flag 4 of the wrapper against the cylindrical surface of the roller 10, and as they are both provided with paste applied thereto before the wrapper delivery begins, they adhere both to said cylindrical surface, and 10 thus they are successively drawn away from the operating surface of the wrapper support as the roller is caused by the preceding wrapper support to rotate in the direction of the arrow (Fig. 4). Thus the wrapper flag is successively bent 15 down from said operation surface when the support moves in the direction of the arrow, and it is not instantly pulled down or released from said surface. Therefore the operating surface of the support may act on the wrapper end and 20 guide it until the wrapping operation is almost completed. On account of its structure, the roller 10 catches, carries and guides the flag of the wrapper and after having been finally released from the operating surface of the support, that 25 is, when it has passed the uppermost position of the roller, the flag of the wrapper is still carried down by the rotating roller and applied to the head of the bunch.

After the wrapper end having been released 30 from the wrapper support, the roller 17 enters the curvature 14 of the continuously rotating cam disc 13 and the surface 22 of the lever arm 21 engages the roller 10, thus arresting its rotary movement. At this moment, if the rear end 35 of the wrapper is provided with an incision, the partly severed part of the wrapper flag has been bent down below the roller as shown in Fig. 3, and the point of the incision may coincide with the apex of the bunch. As the angular position 40 of the cam disc 13 on the shaft 12 can be regulated, it is, however, possible to fix, as desired, the point of time when the surface 22 engages the roller 10.

At this moment the wrapper tension plate 3 45 is held by the arm 29 in its front position adjacent the bunch, as the roller 28 is forced by spring 30 against the concentrical part of the cam disc 25. Now a reversed movement is imparted to the tension plate by means of the cam disc 25, the projection 26 of which forces the lever arm 27 upwards, and a reversed rotary movement as indicated in Fig. 3 is imparted to the roller 10, which rolls upon the surface 22. Then the partly severed flag end of the wrapper 50 resting on roller 10 performs a swinging movement in the direction of the arrow (Fig. 3) round the point of the incision, and is conveyed (carried) by the rotating cylindrical surface of the roller 10 until the point of the part 4 of the flag has left the roller and is completely 55 and correctly wound about the head of the bunch.

If a spring 34 is connected to the roller 10 as 60 illustrated in Fig. 5, the same function is obtained. When the roller is turned in the direction of the arrow (Fig. 4) by engagement with the wrapper support 8, the spring 34 is tightened and, when the wrapper support has released the roller, the latter performs, under the influence of the spring, a reversed rotary movement, thus applying the tip end of the wrapper flag to the head 65 of the bunch.

As illustrated in Fig. 2 the anti-friction carrier may be developed as a roller 10, mounted in the frame 11, adjacent the rolling mechanism.

One end of a spring 35 is secured to the pivot 9, its other end being connected to a bracket 36 carrying the pivot 9.

In operating the device shown in Fig. 2 the wrapper flag is transferred and supplied to the roller in the same manner as previously described and bent down towards the head of the bunch by the rotating roller 10, which rotates tightening the spring 35. When the wrapper support 8 has passed the roller 10 the latter obtains a reversed movement and the part 4 of the wrapper is wound about the head of the bunch.

As illustrated in Fig. 6 the roller 10 engages the upper surface of a bar 37 in the frame 11. When the wrapper tension plate is moved towards the rolling mechanism, as the roller 28 is forced against the concentric circumference of the cam disc 25, the roller engages the upper surface of the bar 37 and is imparted a rotary movement in the direction of the arrow, thus conveying the flag of the wrapper towards the head of the bunch. When the roller 28 is forced outwardly by the projecting portion 26 of the cam disc 25, a reversed movement is imparted to the wrapper tension plate, and thereby the roller 10 rolls on the bar 37 in a reversed direction, thus conveying the last part of the flag of the wrapper to finish the wrapping operation.

I claim:

1. In a cigar-wrapping mechanism, the combination with a bunch rolling mechanism, of a wrapper support, said rolling mechanism and said support having a relative crossing movement whereby a wrapper is delivered by the support to a bunch in said mechanism, a wrapper tension plate, and an anti-friction carrier for conveying the flag of the wrapper in a direction from said tension plate to the bunch head. 105

2. In a cigar-wrapping mechanism, the combination with a bunch rolling mechanism, of a wrapper support, said rolling mechanism and said support having a relative crossing movement whereby a wrapper is delivered by the support to a bunch in said mechanism, and a tension plate having a carrier movably mounted thereon 110 for conveying the flag of the wrapper from said support to the bunch head. 115

3. In a cigar-wrapping mechanism, the combination with a bunch rolling mechanism, of a wrapper support, said rolling mechanism and said support having a relative crossing movement whereby a wrapper is delivered by the support to a bunch in said mechanism, and a tension plate having a downwardly curved end provided with a carrier movably mounted thereon for conveying the flag of the wrapper from said support to the bunch head. 120

4. In a cigar-wrapping mechanism, the combination with a bunch rolling mechanism, of a wrapper support, said rolling mechanism and said support having a relative crossing movement whereby a wrapper is delivered by the support to a bunch in said mechanism, and a tension plate having a rotatable carrier for conveying the flag of the wrapper from said support to the bunch head. 125

5. In a cigar-wrapping mechanism, a wrapper tension plate provided with a wrapper flag carrier, said carrier being movably mounted on said tension plate. 130

6. In a cigar-wrapping mechanism, a wrapper tension plate having a downwardly curved end provided with a wrapper flag carrier, said carrier being movably mounted on said tension plate. 135

7. In a cigar-wrapping mechanism, a wrapper

- 35 tension plate provided with a rotatable carrier for conveying the flag of a wrapper.
- 40 8. In a cigar-wrapping mechanism, a wrapper tension plate provided with a rotatable carrier for conveying the flag of the wrapper and projecting somewhat above said plate.
- 45 9. In a cigar-wrapping mechanism, the combination with a bunch rolling mechanism, of a wrapper support, said rolling mechanism and said support having a relative crossing movement whereby a wrapper is delivered by the support to a bunch in said mechanism, a wrapper tension plate, and an anti-friction carrier mounted adjacent the rolling mechanism for conveying the flag of the wrapper in a direction from said tension plate to the bunch head.
- 50 10. In a cigar-wrapping mechanism, the combination with a bunch rolling mechanism having rotatable rolls, of a wrapper support, said rolling mechanism and said support having a relative crossing movement whereby a wrapper is delivered by the support to a bunch in said mechanism, and a carrier, said carrier being rotatably mounted adjacent to said rolling mechanism and adapted to turn in the opposite direction to that of said rolls for conveying the flag of the wrapper from said support to the bunch head.
- 55 11. In a cigar-wrapping mechanism, the combination with a bunch rolling mechanism, of a wrapper support, said rolling mechanism and said support having a relative crossing movement whereby a wrapper is delivered by the support to a bunch in said mechanism, a wrapper tension plate, a rotary carrier for conveying the flag of the wrapper from said support to the bunch head, and means for imparting to said carrier a reversed rotary movement on finishing the applying of the wrapper flag to the bunch head.
- 60 12. In a cigar-wrapping mechanism, the combination with a bunch rolling mechanism, of a wrapper tension plate having an oscillating movement to and from said rolling mechanism, a wrapper flag carrier, said carrier being movably mounted on said plate, and means for imparting to said carrier a reversed movement when said plate is adjacent to said rolling mechanism.
- 65 13. In a cigar-wrapping mechanism, a wrapper tension plate provided with a spring actuated wrapper flag carrier.
- 70 14. In a cigar-wrapping mechanism, the combination with a bunch rolling mechanism, of a wrapper tension plate having an oscillating movement to and from said rolling mechanism, a rotatable wrapper flag carrier, and a stationary member adjacent said rolling mechanism adapted to periodically engage said carrier.
- 75 15. In a cigar-wrapping mechanism, the combination with a bunch rolling mechanism, of a wrapper tension plate having an oscillating movement to and from said rolling mechanism, a rotatable wrapper flag carrier, a movable member adjacent said rolling mechanism, and means for periodically bringing said member into engagement with said carrier.
